UNITED STATES PATENT OFFICE

ARTHUR J. BAKER, OF TOLEDO, OHIO, ASSIGNOR TO THE WILLYS-OVERLAND COMPANY,
OF TOLEDO, OHIO, A CORPORATION OF OHIO

DESIGN FOR A COMBINED AUTOMOBILE FENDER AND HEAD LAMP

Application filed September 10, 1932. Serial No. 44,806. Term of patent 14 years.

To all whom it may concern:

Be it known that I, ARTHUR J. BAKER, a citizen of the United States, residing in the city of Toledo, county of Lucas, and State of Ohio, have invented a new, original, and ornamental Design for Combined Automobile Fender and Headlamp, of which the following is a specification, reference being had to the accompanying drawing, forming part thereof.

In the drawing, Figure 1 is a perspective view of the combined automobile fender and headlamp showing my new design;

Figure 2 is a top plan view of the fender and headlamp combination illustrated in Figure 1; and

Figure 3 is a front elevational view of the fender and headlamp shown in Figure 1.

My design is particularly characterized by the relative position of the headlamp with respect to the crown of the fender, the angularity of the headlamp lens and the blended curved surfaces of the fender proper and the headlamp housing arrangement.

I claim:

The ornamental design for a combined automobile fender and headlamp substantially as shown and described.

In testimony whereof, I affix my signature, this 6th day of September, 1932.

ARTHUR J. BAKER.
